CLAIM

The ornamental design for a hunting seat, as shown and described.

DESCRIPTION

FIG. 1 is a top perspective view of the hunting seat incorporating my new design;

FIG. 2 is a bottom perspective view thereof;

FIG. 3 is a top plan view thereof;

FIG. 4 is a bottom plan view thereof;

FIG. 5 is a left side view thereof;

FIG. 6 is a front view thereof; and,

FIG. 7 is a rear view thereof.

The broken lines illustrate portions of the hunting seat that form no part of the claimed design.
